UNITED STATES PATENT OFFICE.

WILLIAM S. MCCLINTIC, OF PITTSBURGH, PENNSYLVANIA, ASSIGNOR TO JONES & LAUGHLIN STEEL CORPORATION, OF PITTSBURGH, PENNSYLVANIA, A CORPORATION OF PENNSYLVANIA.

FABRICATED STRUCTURAL MEMBER.

Application filed June 27, 1922. Serial No. 571,157.

My invention aims to strengthen and improve rolled structural members of open web or trussed form, and to enable such members to be readily and cheaply fabricated and utilized for building and other purposes.

In the accompanying drawings, wherein I have shown one embodiment of my invention for purposes of illustration, Fig. 1 is a side view of a trussed web I-beam such as is suitable for floor beams, roof trusses, bridge girders, and other structural purposes; Fig. 2 is an enlarged side view of one end of the beam shown in Fig. 1; Fig. 3 is a cross-section of the same on the line 3-3 in Fig. 2; and Fig. 4 is a top view of one end portion of the same beam; Figs. 2, 3 and 4 being drawn to the same scale; and Fig. 5 is a perspective view of a securing clip.

The invention may be applied to I-beams, channels, Z-sections, T-sections, H-sections, and other shapes with and without flanges, having trussed or open webs formed integrally with the flanges or continuous margins. In the particular embodiment selected for illustration herein and shown in the drawings, referring particularly to Fig. 1, the invention is embodied in a trussed I-beam 11 having flanges 12 connected by angularly disposed lattice or web members 13 formed integrally with the flanges by any suitable process of manufacture. Preferably each end of the beam is strengthened by securing to the flanges suitable shear plates 14, disposed one on each side of the web, although it is not essential that shear plates be secured on both sides of the web. These shear plates have flanges 15 which fit against and are secured to the inner sides of the flanges 12. The preferred manner of securing the flanges 15 and the flanges 12 to each other is by a series of clips 16 having studs 17 fitting through alining notches 18 in the contacting flanges, as illustrated in Figs. 2, 3 and 4, and drawing the members snug together. The clips are preferably fabricated with the studs 17 straight, as shown in full lines in Fig. 5, and are bent under the flanges by a hammer or other suitable means readily available at the place of use.

The shear plates are preferably made of a length about equal to the depth of the web, and the connections to the flanges of

the element are spaced to hold the shear plates and flanges securely against forces tending to distort the end portion of the fabricated structure in any and every direction.

Fabricated structural members embodying my invention may advantageously be substituted for solid web members wherever lightness and strength are desirable. In buildings and other structures the open webs permit pipes, wires, conduits and other accessories and structural parts to be run through the beams where they are out of the way of other members and within the minimum clearance limits. The shear plates not only strengthen the ends of the beam or other element to enable it to carry its maximum load with safety, but enable connections with other portions of the structure to be made as strong as with solid web beams.

If desirable, shear plates may be applied to beams and other elements between their ends, and are advantageously used wherever there is a point of support or connection with some other portion of the structure in which the element is embodied.

In fabricating structural members embodying my invention, it is customary to roll the integral elements in continuous lengths sufficient for several members, and cut them in lengths to suit the particular use, the shear plates being secured either at the place of manufacture or place of use, as most convenient.

My invention obviously is not restricted to the particular embodiment thereof herein illustrated and described.

Having described one illustrative embodiment of my invention, what I claim and desire to secure by Letters Patent is as follows:

1. A structural element comprising continuous side marginal flanges connected by web members integral therewith together constituting a jointless truss, and provided with supplementary shear members at spaced points, said shear members being formed with end flanges and fitted between the flanges on each side of said element and rigidly secured thereto by means of clips embracing and gripping said contiguous flanges at each margin of said structural elements.

2. A structural element comprising con-

- tinuous side margins connected by web members integral therewith together constituting a jointless truss, and provided with supplementary shear members at spaced points, 5 said shear members being bent along their sides to form flanges and rigidly secured thereby to the said side margins by means of clips embracing said margins and flanges.
3. A structural element having parallel 10 sides connected by an open web integral therewith, said sides and web together constituting a jointless truss, and shear plates having edge holding means arranged in pairs on opposite sides of said web at spaced 15 points to cover openings therein, and rigidly secured to said sides by means of clips embracing them and engaging said holding means.
4. A structural element having parallel 20 sides connected by an open web integral therewith, and stiffening members connected to said sides at spaced intervals by means of clips, said sides and stiffening members be-

ing provided with registering notches to receive and position said clips. 25

5. A flanged rolled structural member having an open web of truss-like form connecting its flanges and alining notches in opposite flanges adapted to receive clips for securing stiffening members thereto, stiffeners having spaced notches corresponding to the notches in said flanges, and clips positioned in said notches for securing said stiffeners to said structural members. 30

6. In combination with a rolled flanged 35 member having an open web and stiffeners adapted to fit between the flanges on opposite sides of said web, said flanges and stiffeners having alining notches in their adjacent edges, and clips embracing said notched 40 edges and having studs projecting through said notches and bent under them.

In testimony whereof, I have signed my name to this specification.

WILLIAM S. McCLINTIC.
